UNITED STATES PATENT OFFICE.

WILLIAM B. DURGIN, OF CONCORD, NEW HAMPSHIRE.

DESIGN FOR A HANDLE FOR A SPOON OR FORK.

SPECIFICATION forming part of Design No. 12,380, dated August 2, 1881.

Application filed May 9, 1881. Term of patent 3½ years.

To all whom it may concern:

Be it known that I, WILLIAM B. DURGIN, of Concord, county of Merrimack, State of New Hampshire, have invented and produced a new and original Design for the Handles of Table-Ware, such as Spoons and Forks, of which the following description, in connection with the photographic illustration, is a specification.

The photograph shows a front view of a spoon with a handle, the subject of this design.

The shank portion *a* of the handle, connected with the bowl *b* of the spoon or the tines of a fork, as the case may be, consists of a twist of substantially uniform diameter from end to end. At the point where the shank connects with the handle portion *d* a ridge, *c*, is formed, separating the shank *a* and handle portion *d* from one another, and forming a proper support for the said handle portion, which is formed as a thick flat plate with straight sides inclined outward from the point *c*, where it connects with the shank, to its extremity *e*, which is made as the arc of a circle of small curvature, the sides of the handle being nearly normal thereto, the said handle widening gradually from its point of connection with the shank to its extremity. The handle is made thick and heavy, and has a broad bevel, 2, extending entirely around its edges and end *e*. The beveled portion 2 is ornamented with geometrical facets *f*, giving a series of brilliant reflections, they being formed in a ground, *g*, traversed by fine parallel lines or hatchings. The ornaments in the bevel portion of the sides of the handle are separated from those at the end *e* of the handle by lines 3. The top face, *l*, of the handle is provided with delicate

ornaments *m*, (shown as a connected line of trefoils or clover-leaves extended along its edges,) the curved end portion of the said handle being plain. The entire rear side of the handle (not shown in the photograph) may be perfectly plain.

I claim—

1. The shank portion *a*, and flat handle *d* separated therefrom by a ridge, *c*, and having straight sides inclined outward or widening from the shank to the tip, which is formed at the end as an arc of a circle, *e*, in the plane of the handle-plate and joining the said inclined sides, substantially as described. 45

2. The shank portion formed as a twist, the handle portion formed as a flat plate with straight sides widening from the part adjacent to the shank to the end and beveled at its edges and end, substantially as described. 55

3. The handle formed with straight sides widening toward the end, which is made as the arc of a circle and beveled at its sides and ends, the beveled portion being provided with the ornaments *f*, as shown and described. 60

4. The handle with the straight sides and curved end, the said sides and end being beveled and provided with ornaments *f*, and the face being provided with the ornamental lines *m*, as shown and described, along its edges and having its middle portion plain. 65

In testimony whereof I have signed my name to this specification in the presence of two subscribing witnesses.

WM. B. DURGIN.
